UNITED STATES PATENT OFFICE.

ADOLPH A. GAZDA, OF CHICAGO, ILLINOIS, ASSIGNOR TO KAESTNER & HECHT COMPANY, OF CHICAGO, ILLINOIS, A CORPORATION OF ILLINOIS.

SWITCH.

1,425,003.

Specification of Letters Patent. Patented Aug. 8, 1922.

Application filed September 20, 1920. Serial No. 411,635.

To all whom it may concern:

Be it known that I, ADOLPH A. GAZDA, a citizen of the United States, residing at Chicago, in the county of Cook and State of Illinois, have invented certain new and useful Improvements in Switches, of which the following is a specification.

My invention relates to control switches for electrical equipment, and more specifically to an improved and simplified switch embodying unitary means for damping the movement of the armature toward the pole and also for preventing too close contact between the armature and the pole when the switch is closed.

In electrical switches, a movable armature is attracted toward a pole piece by the delivery of electrical energy to a suitable coil surrounding the pole. The movable armature is ordinarily mechanically connected through one or more links to a pneumatic or hydraulic dash pot or damping device which prevents too rapid movement of the parts and eliminates noise and rattling. If there is any looseness in the mechanical connections between the dash pot piston and the armature, however, it will be obvious that this allows relative movements between the parts which are not damped in any way. It is also necessary that the armature should not lie in actual contact with the pole piece when the switch is closed, as if it does, there is apt to be developed sufficient residual magnetism to hold the parts in contact and make the switch stick when it should open. According to my invention a single element functions both as a damping means and as a stop to hold the armature properly spaced from the pole. In the accompanying drawings Figure 1 is a section of so much of an electric switch as is necessary to illustrate the application of my invention thereto. Fig. 2 is a fragmentary view of the same parts with the armature in the open position.

In the embodiment of my invention selected for illustration a suitable pole piece 10 of magnetic material is surrounded by a suitable coil 12 by means of which flux may be generated in the pole to operate the switch. The face of the pole has a central hole or socket 14 extending into the pole and receiving the combined damping element

and stop made up of a pin 16 of magnetic material rigidly fastened in a shell 18 of non-magnetic material. The shell 18 has a loose sliding fit in the hole 14.

The operation of my device is as follows: With the parts in closed position as shown in Fig. 1 the armature 20 is firmly held against the end of the pin 16 by the magnetic force acting thereon, which pin projects beyond the face of the pole and acts as a stop for the armature. The shell 18 rests firmly on the bottom of the socket and it will be seen that the structural elements resisting the magnetic force are disposed along the line of that force and properly supported so as to resist it. When the current is interrupted the armature falls back to the position shown in Fig. 2. The pin 16, which rests in actual contact with the armature but is separated from pole 10 by the non-magnetic shell, has sufficient residual magnetism to hold it in contact with the armature and draw it out into the position shown in Fig. 2, the space at the bottom of the pole being filled by air which flows in around the shell. When the power is subsequently turned on the air pocketed in the bottom of the hole has to escape in the same way it entered, thus strongly damping the inward movement of the armature, until a positive limit is imposed on further movement by contact between the shell and the bottom of the hole.

The extreme simplicity of my device will be apparent. There are no mechanical connections to wear or get out of order and the single unitary device made up of a small shell with a pin in it, performs the functions hitherto obtained by the use of complicated linkages, and dash pots structurally independent of the switch itself, as well as functioning as a positive stop for the armature. As the pin is in contact with the armature at the beginning of its movement toward closed position, there is nothing to rattle by reason of lost motion at the beginning of the closing movement.

While I have illustrated and described in detail the preferred embodiment of my invention, it should be clearly understood that the disclosure is merely for purposes of illustration and that many modifications and variations will naturally occur to those

skilled in the art. I aim in the subjoined claims to cover all such legitimate variations and modifications.

I claim as my invention:

- 5 1. The combination of a movable switch member of magnetic material, an electromagnet including a stationary pole piece arranged to move said switch member, said pole piece having a socket in its face, and
- 10 10 a damping plunger loosely slideable in said socket, the movement of said plunger in either direction being effected by the switch member.
- 15 2. A switch and stop means therefor comprising, in combination, a pole piece having a socket in its face and a slideable element in said socket of a length sufficient to hold the armature spaced from the pole.
- 20 3. A switch comprising, in combination, a pole piece having a socket in its face opposite the armature and a slideable plunger reciprocating in said aperture, a portion of said plunger in contact with said armature being of magnetic material and having sufficient residual magnetism to cause said plunger to follow the armature in its outward movement.
- 25 4. A switch having, in combination, a pole piece, a socket in the face of the pole piece, a shell of non-magnetic material having a loose sliding fit in said socket and a core of magnetic material rigidly mounted in said shell.
- 30 5. In electro-magnetic devices for producing mechanical movement, two magnetic elements mounted for relative movement by means of the magnetic forces acting between them and a third element having continuous sliding contact with one of said elements and magnetically held in contact with the other of said elements throughout the operation of the device.
- 35 6. In electro-magnetic devices for producing mechanical movement, two magnetic elements mounted for relative movement by means of the magnetic forces acting between them and a third element having continuous sliding contact with one of said elements and magnetically held in contact with the other of said elements throughout the operation of the device.
- 40 7. In electro-magnetic devices for producing mechanical movement, two magnetic elements mounted for relative movement by means of the magnetic forces acting between them and a third element having continuous sliding contact with one of said elements and magnetically held in contact with the other of said elements throughout the operation of the device, and means for cushioning the two elements having a sliding connection.
- 45 8. In electro-magnetic devices for producing mechanical movement, two magnetic elements mounted for relative movement by means of the magnetic forces acting between them and a third element having continuous sliding contact with one of said elements and magnetically held in contact with the other of said elements throughout the operation of the device, and means for cushioning the two elements having a sliding connection.
- 50 9. In electro-magnetic devices for producing mechanical movement, two magnetic elements mounted for relative movement by means of the magnetic forces acting between them and a third element having continuous sliding contact with one of said elements and magnetically held in contact with the other of said elements throughout the operation of the device, and means for cushioning the two elements having a sliding connection.
- 55 10. In electro-magnetic devices for producing mechanical movement, two magnetic elements mounted for relative movement by means of the magnetic forces acting between them and a third element having continuous sliding contact with one of said elements and magnetically held in contact with the other of said elements throughout the operation of the device, and means for cushioning the two elements having a sliding connection.

them and a third element having continuous sliding contact with one of said elements and magnetically held in contact with the other of said elements throughout the operation of the device, and means for limiting the movement of said first mentioned elements toward each other by limiting the movement of the third element with respect to the element on which it slides.

8. A switch having, in combination, a pole piece, a socket in the face of the pole piece, a shell of non-magnetic material having a loose sliding fit in said socket and a core of magnetic material rigidly mounted in said shell, said shell terminating flush with the face of the pole piece when in contact with the bottom of the socket and said core projecting slightly beyond the plane of the outer end of the shell.

9. A switch having, in combination, a pole piece, a socket in the pole piece, a shell of non-magnetic material in the socket, and a core of magnetic material in the shell.

10. In electro-magnetic devices for producing mechanical movement, a fixed structure, a movable structure, an element having damped movement with respect to said fixed structure and magnetic means for causing said element to follow the movements of said movable structure.

11. In electro-magnetic devices for producing mechanical movement, a movable structure, an element supported for damped movement, said element being movable with said movable structure by means of residual magnetism.

12. In electromagnetic devices for producing mechanical movement, a fixed structure having a socket in its face, a movable structure, an element smaller in cross section than said socket and slideable therein, and means for moving said element whereby an annular flow of air about said element will ensue.

13. In electro-magnetic devices for producing mechanical movement, a fixed structure, a movable structure, an element slideable with respect to said fixed structure for damped movement through a certain range terminating in a rigid stop, and means operating by residual magnetism for moving said element with the movements of said movable structure.

In testimony whereof, I have hereunto set my hand.

ADOLPH A. GAZDA.
